UNITED STATES PATENT OFFICE

HERBERT G. KAMRATH, OF FLINT, MICHIGAN, ASSIGNOR TO A C SPARK PLUG COMPANY, OF FLINT, MICHIGAN, A COMPANY OF MICHIGAN

FUEL PUMP

Application filed June 27, 1928. Serial No. 288,780.

As will be understood from the above title, this invention relates to fuel pumps such as are currently employed upon automotive vehicles, and elsewhere in connection with internal combustion engines; and it is a particular object of this invention to provide simple and effective intermediate means for the transmission of motion from a pump actuating element, such as an oscillating lever, to a pump diaphragm or the like.

Although the present invention is herein described with particular reference to a diaphragm pump of the general character described and claimed in a pending application of Abraham M. Babitch, Ser. No. 123,370, filed July 19, 1926, it should be understood that the principles of said invention are believed to be applicable to other reciprocatory pumps in which provision may be made for use of resilient means to effect an expulsion stroke of a pumping element, the intake stroke thereof being positively effected but variable in length,—diminishing as a pressure is built up by the operation of the pump.

Other objects of this invention, all forms of which involve the use of some flexible but substantially inextensible linear element interposed between a part such as a so-called diaphragm stem and a rotating or a reciprocating actuating element, may be best appreciated by the following description of an illustrative embodiment thereof, taken in connection with the appended claims and accompanying drawings.

Fig. 1 may be referred to as a substantially median vertical section through a fuel pump illustrating this invention.

Fig. 2 is a partial view corresponding to a central portion of Fig. 1 but showing an alternative form.

Referring first to conventional parts of the fuel pump illustrated in Fig. 1, a main structural element in the form of a body casting 1 and a subsidiary structural element in the form of a cover casting 2 are shown as cooperating in the retention of a flexible diaphragm 3, adapted to serve as reciprocatory pumping element,—effective to vary the cubic contents of a pump chamber 4, shown as provided in the cover casting 2.

The cover casting is shown as provided not only with inlet passages 5, 5', 6 and 7 and with outlet passages 8, 8', but also with means for supporting a filter cup or sight cup 9, adapted to retain filters 9'.

An oscillable actuating element in the form of a lever 10, pivoted at 11 to the main casting 1, is shown as engageable by some moving part,—which may be, for example, a cam 12 on a camshaft or a crankshaft 13, or some other rotated or reciprocatory element. Means such as a compression spring 14, interposed between a cupped disc 15, secured at the bottom of the main casting 1, and an oppositely cupped disc 15', engageable by an inner end or arm 21 of the lever 10, may be employed resiliently and constantly to hold the opposite end of said lever in engagement with the cam 12.

Inlet valve 16 and outlet valve 17 being provided in the respective passages leading to and from the pump chamber 4, and the diaphragm 3 being suitably attached to a handling part such as a slideable rod or so-called diaphragm stem 18, the present invention more particularly relates to novel and advantageous means, interposed between the diaphragm handling element 18, or its equivalent, and a portion such as the inner end 21 of an actuating element 10.

For the purpose last referred to, a flexible but substantially inextensible linear element 22, which may be a suitable tape, a leather or textile or woven wire strip, or even a thin and pliable strip of metal, or the like, may be attached at or near its ends, and in any suitable way, to terminal portions of the diaphragm stem 18 and the lever arm 21. For example, use may be made of means such as a bolt 23, shown as extending through a reduced and rounded terminal portion of the stem 18, and a screw 24, shown as extending into the end of the lever arm 21 (optionally rounded somewhat as suggested at 25) and the length of the element 22 may be such as to produce a complete intake movement of the reciprocatory pumping element 3 during each rotation of the cam 12, unless this pumping element is held down by pressure built up within the chamber 4. The described

parts are so related that each reciprocatory movement of the arm 21 may, however, produce a flexing or buckling of the strip 22, somewhat as suggested by the dotted lines 22'; and it is accordingly important that said strip be formed of a material that can undergo repeated bending without avoidable deterioration.

In the alternative embodiment of this invention shown in Fig. 2, the lower end of a diaphragm stem 18^a and the inner end 21^a of a lever 10^a being respectively slotted and provided with transverse pins 27^a, 28^a, these pins are shown as connected by a flexible but substantially inextensible thrust-refusing intermediate element in the form of a woven or twisted cord or cable 29^a—the ends thereof being shown as looped about the respective pins 27^a, 28^a, and as suitably wrapped at 30. The construction here referred to is such that, whether or not the respective ends of the flexible element 29^a undergo a slight rotative movement during each reciprocation of the lever 10^a, or its equivalent, said element 29^a may be flexed, substantially as indicated by the dotted lines 29^a', at such times as the upward stroke of the diaphragm stem 18^a may be prevented by the building up of a pressure within a pump chamber.

As compared with thrust-refusing intermediate means in the form of rigid links, the above described use of a linear element in the form of a single length of lap of a material which is so flexible as to bend under thrust but so inextensible as to reliably transmit a tension has the important advantage of complete silence during operation, and, unless the mentioned flexible element is formed of resilient material, neither its weight nor its elasticity need be taken into consideration in the calibration of the spring 19 or the spring 14, for a desired effect. It is an obvious merit of the illustrated mode of attachment of the desired linear elements that the resultant bends therein are slight when said linear elements are under tension. The suggested rounding of corners engaging said linear elements may accordingly be regarded as optional, and the exact mode of attachment of the mentioned ends may be regarded as a matter of subordinate importance,—assuming that 22 is not a part of 18.

Although the foregoing description has included but two embodiments of the present invention, it will be obvious that numerous additional modifications might easily be devised, without involving the slightest departure from the spirit and scope of the invention as the same is indicated above and in the following claims.

I claim:

1. In a pump of that type which includes a pressure-responsive reciprocatory pumping element, movable in one direction in a pump chamber by means including an attached

part and conditionally advanced in the opposite direction by resilient means: actuating means having a uniform throw; and intermediate means, in the form of a single-length linear element formed of a substantially inextensible material, so flexible as to bend under thrust but so inextensible as to transmit a tension, interposed between and terminally secured to said attached part and said actuating means and thereby serving to impart variable strokes to said attached part.

2. In a pump of that type which includes a pressure-responsive reciprocatory pumping element, movable in one direction in a pump chamber by means including a slideable rod and conditionally advanced in the opposite direction by resilient means: actuating means having a uniform throw; and intermediate means in the form of a single-length linear element formed of a substantially inextensible material, so flexible as to bend under thrust but so inextensible as to transmit a tension, interposed between said slideable rod and said actuating element and thereby serving to impart variable strokes to said attached part, the ends of said linear element being so attached to said slideable rod and to said actuating means that bends therein are slight when said linear element is under tension.

In testimony whereof I affix my signature.
HERBERT G. KAMRATH.
